76 C3 C C⁴ Inventor:
Sigmund Lyons,
By his Attorney, Geo. W. Elliott

UNITED STATES PATENT OFFICE.

SIGMUND LYONS, OF NEW YORK, N. Y.

SAFETY APPLIANCE FOR AUTOMOBILES.

1,413,042.

Specification of Letters Patent. Patented Apr. 18, 1922.

Application filed February 10, 1921. Serial No. 443,846.

To all whom it may concern:

Be it known that I, SIGMUND LYONS, a subject of the King of England, and a resident of the borough of Manhattan, city, county, and State of New York, have invented certain new and useful Improvements in Safety Appliances for Automobiles, of which the following is a specification.

My invention is designed to afford simple but effective means whereby an automobile using gasoline as the motive power may be safeguarded against clandestine or unlawful use, and the invention consists essentially in rendering the machine inoperative or operative by the withdrawal or insertion of a key to locking and releasing mechanism by which the supply of gasoline to the carburetter is controlled, as well as the electrical circuits involved, substantially as hereinafter set forth.

In the accompanying drawings,

Fig. 1, is a sectional elevation illustrating the correlation of my safety appliance to an auto-gasoline tank, dashboard, etc.;

Fig. 2, is a view on a larger scale with the casing closure plate removed, showing my control mechanism in elevation;

Fig. 3, is a vertical sectional elevation taken upon general plane of line 3—3, Fig. 6;

Fig. 4, is a transverse section taken upon plane of line 4—4, Fig. 2;

Fig. 5, is a transverse section taken upon plane of line 5—5, Fig. 2;

Fig. 6, is a transverse section taken upon general plane of line 6—6, Fig. 3;

Fig. 7, is a sectional detail on a large scale, of the gasoline control valve;

Fig. 8, is a perspective view showing one of the hasps for securing the casing closure plate;

Fig. 9, is a transverse section taken upon plane of line 9—9, Fig. 3;

Fig. 10, is a diagram showing the electric circuits.

D, represents the dashboard, and D¹, the rear wall or partition of the engine compartment of an automobile. T, represents a gasoline tank which may be of either the gravity or vacuum type, connected with the carburetter (not shown) by a transfer pipe t, in a manner well known in the art. For convenience of illustration the tank T, is shown as positioned on the aforesaid partition D¹, although its location is not material to the invention.

C, is the casing enclosing the main actuating parts of my control mechanism, said casing being closed normally by a side plate c, which may be screwed (as at c¹) or otherwise detachably secured to the casing C, so as to afford access thereto when necessary, provided said cover c, is not internally locked in position as hereinafter set forth.

The casing C, is permanently secured to the partition D¹, by means of bolts or screws c², c³, applied and accessible only within the casing C, as indicated in Fig. 3, so that the casing cannot be detached and removed from the partition D¹, while the closure plate c, is intact and rigidly secured to the casing C.

Positioned longitudinally within the casing C, is a rock shaft R, mounted in fixed bearings c², c³. In Fig. 3, of the drawings, this rock shaft R, is shown as tubular, but this is not an essential construction provided the coupling end thereof is recessed to receive one extremity of the actuating tongue l, the other end of which is rigidly attached to the semi-rotatable barrel of a lock L, preferably of the pin type, although any lock the key of which can only be withdrawn therefrom when the parts of its mechanism are in closed or locked relationship will answer the purpose.

In the construction shown in the drawings, at least the end of the lock tongue l, which engages with the rock shaft R, is relatively broad and flat, or approximately so, and fits into a correspondingly shaped transverse slot r¹, formed for its reception in this extremity of the rock shaft R, as will be seen by reference more particularly to Figs. 3 and 9, although any means of connecting the rock lever R, and the lock tongue l, in such manner that they will oscillate together will answer the purpose of my invention, the distinctive feature in this respect being a rockable shaft controlled and actuated by an extension of the lock L.

The latter is by preference located on the dashboard D, and is connected with the works casing by a tubular shield l¹, which isolates and protects the actuating rod or tongue l, so that it cannot be tampered with by extraneous means.

One or more hasp hooks r¹, r², are rigidly and radially secured to the rock shaft R, for engagement with staples c², c³, on the inner side of the cover plate c, when the latter is in position on the casing C, and the said rock shaft is in otherwise retracted

position. What may thus be designated as the normal position of the parts (that in which the car is inoperative) is illustrated in Figs. 2, 3, 4, 5, 6, 8 and 9.

Conversely, when the key *k*, is in the lock *L*, and is given a half turn the shaft *R*, is likewise rotated on its longitudinal axis to that extent. As a result the circuit closer *c*⁴, rigidly mounted on said rock shaft *R*, in operative alignment with the spring terminal jaws *e*, *e*, upon the insulating block *c*⁵, in the casing *C*, is interposed between the said terminal jaws *e*, *e*, thereby rendering the spark plug or ignition system, and the 10 starter motor system of the car operative, as will be understood by reference to the circuit diagram Fig. 10.

Simultaneously with this operation, the partial rotation of the rock shaft *R*, as above stated causes the cam *r*⁶, on the rock shaft *R*, to act against the shoulder *v*, on the portion of the valve stem *v*¹, within the casing, thereby raising the lower end of said valve stem *v*¹, preferably bevelled to act as a needle valve *v*², away from the valve seat *t*, said valve seat *t*, being positioned in the lower part of a stand tube *t*¹, which is connected with the casing *C*, and extends through the gasoline tank *T*—inlets *t*², *t*², being formed in said stand tube *t*¹, above the valve seat *t*, for the flow of gasoline (when the valve *v*², is open) to and through the conduit *v*³, to the carburetter in a manner well known in the art. A spring *t*³, interposed between a shoulder *v*⁴, on the valve rod *v*¹, and the cap at the upper end of the stand tube *t*¹, tends constantly to hold the valve *v*², to its seat, as shown in Fig. 3.

The releasing of the operative parts by 40 the turning of the key *k*, as above set forth, also results in the withdrawal of the hasp hooks *r*¹, *r*¹, from the staples *c*³, *c*³, on the inside of the cover plate *C*, so that the latter can be unscrewed and removed if access is 45 required to the parts inside the casing *C*, if desired. This of course cannot be done when the hasp hooks *r*¹, *r*¹, are in engagement with the staples *c*³, *c*³, as is normally the case when the key *k*, is withdrawn from the 50 lock *L*.

From the foregoing it will be seen that in the absence of the key *k*, the auto-car is inoperative, and that a simple half turn of the key *k*, in the lock *L*, renders the car available for immediate use. Furthermore the operative parts of my control mechanism are isolated and protected, and cannot be tampered with unless actually ruptured or destroyed.

60 What I claim as my invention and desire to secure by Letters Patent is,

1. An automobile safety appliance of the character designated, comprising a casing, a lock, a rock shaft enclosed in said casing, and controlled by said lock, a valve stem

with a shoulder, a cam on said rock shaft, adapted to contact with the shoulder on the valve stem positioned in part in said casing, said valve stem forming a part of a valve positioned in a gasoline tank and controlling the supply of gasoline to the carburetter, a spring which tends normally to close said valve, a closure plate and means for locking the same, the locked condition of said closure plate being controlled by said rock shaft for the purpose described. 70

2. An automobile safety appliance of the character designated, comprising a casing, a lock, a rock shaft enclosed in said casing, and controlled by said lock, a valve stem 80 with a shoulder, electric terminals positioned in said casing and forming part of an electric circuit connected with the sparking motor starter, and light systems of the car, a circuit closer on said rock shaft, a cam on said rock shaft, adapted to contact with the shoulder on the valve stem positioned in part in said casing, said valve stem forming a part of a valve positioned in a gasoline tank and controlling the supply of gasoline 85 to the carburetter, a spring which tends normally to close said valve, a closure plate and means for locking the same, the locked condition of said closure plate being controlled by said rock shaft, for the purpose 90 described. 95

3. An automobile safety appliance of the character designated, comprising a casing, a lock, a rock shaft enclosed in said casing, and controlled by said lock, a valve stem 100 with a shoulder, electric terminals positioned in said casing and forming part of an electric circuit connected with the sparking, motor starter, and light systems of the car, a circuit closer on said rock shaft, a cam 105 on said rock shaft, adapted to contact with the shoulder on the valve stem positioned in part in said casing, said valve stem forming a part of a valve positioned in a gasoline tank and controlling the supply of gasoline 110 to the carburetter, a spring which tends normally to close said valve, a closure plate and a hasp hook rigidly secured to said rock shaft and a staple of the closure plate of the casing with which said hasp hook engages for the purpose described. 115

4. In an automobile safety appliance of the character designated, the combination of a rock shaft, a lock for actuating and controlling same, a casing enclosing the rock 120 shaft, electric terminals positioned within said casing, a gasoline supply valve, a circuit closer on said rock shaft adapted to contact with said electrical terminals, and means on said rock shaft for controlling the gasoline supply valve extraneously positioned in a gasoline tank, for the purpose 125 described.

5. In an automobile safety appliance of the character designated, the combination 130

of a rock shaft, a lock for actuating and controlling the same, a casing enclosing the rock shaft, electric terminals positioned within said casing, a gasoline supply valve, together with means on the said rock shaft 10 and closure plate for internally securing the closure plate of the casing, for the purpose described.

- 5 a circuit closer on said rock shaft adapted to contact with said electrical terminals, and means on said rock shaft for controlling the gasoline supply valve extraneously positioned in a gasoline tank, a closure plate to-
